UNITED STATES PATENT OFFICE.

GEORGE R. LEWERS, OF BROOKLYN, NEW YORK, ASSIGNOR TO GENERAL CHEMICAL COMPANY, OF NEW YORK, N. Y. A CORPORATION OF NEW YORK.

ELECTRODE.

Application filed October 11, 1922. Serial No. 593,690.

My invention relates to electrodes, and more particularly to electrodes for use in precipitators of the type commonly known as Cottrell precipitators, and has for its object to provide a discharge electrode of simplified and novel construction, whereby an electric corona of increased efficiency as a precipitating medium is created in practice. The invention contemplates further an electrode construction which permits the electrode supporting means to be simplified without interfering with the efficiency of the precipitator. Other objects of my invention will appear from the description hereinafter and the features of novelty will be pointed out in the appended claims.

In the accompanying drawings, which illustrate a specific embodiment of the invention without defining its limits, Figure 1 is a sectional view illustrating a precipitator with my improved electrode included therein; Fig. 2 is an enlarged view of the electrode, partly in section, and Fig. 3 is a cross-section on the line 3—3 of Fig. 2.

In connection with discharge electrodes of the type in question, several problems present themselves for solution before a satisfactory result is obtained; for instance, the greater the number of discharge points upon the surface of the electrode, the more efficient will be the resulting electrical corona when the electrode is in use; furthermore, the electrode must possess a certain stability in the direction of its length in practice. With these points in mind, discharge electrodes have been constructed in the form of rods of lead having a star shape in cross-section; because of the pliability of the lead, it has been necessary to construct such electrodes with cores of iron in order to secure the desired stability; electrodes so constructed, because of their weight, have a tendency to whip under electrical stresses when the precipitator is in operation, and consequently must be held at the bottom.

All of these disadvantages and objections are overcome in the present case, in which the electrode itself comprises a preferably metallic shell illustrated in the form of a tube of lead 5, the outer surface of which is finely serrated or fluted in the direction of its length to provide a multiplicity of discharge points 6, as shown in Fig. 3; the op-

posite end of the tube 5 are closed by means of lead caps 7. The tube 5, at one end, extends through a sleeve 8 having a covering 9 of lead and of larger diameter internally than the external diameter of the tube 7, which is fixed in said sleeve by a filling of lead 10 which is poured into the annular space between said sleeve and tube in a molten state, the lower end of said sleeve, about the tube, being temporarily closed in any suitable manner, as by being plugged with a packing of oakum during the time the lead is being poured; a pin 11 extends transversely through the sleeve 8 near its one end and through the tube 5 to support the latter against lengthwise movement relatively to said pipe. The sleeve 8 is screw-threaded at its one end for connection with the supporting element which, in the illustrated example, is shown in the form of a ship channel 12 provided with a covering of lead 13; a cap of lead 14 is formed on the projecting end of the electrode 5 by pouring molten lead into a suitable mold temporarily placed in position and encloses the upper end of the sleeve 8 and the opposite ends of the pin 11.

With this arrangement, the electrode is freely suspended and extends into the customary collecting electrodes 15, it being understood that an operative precipitator may include a plurality of electrodes, the discharge electrodes being suspended at spaced intervals, for instance, from the ship channel 12, as shown. Because of the serrated or fluted construction of the tubes 5, the same possess sufficient inherent stability to render the use of cores of any description unnecessary; for the same reason, the lower ends of said tubes need not be held, but on the contrary, said tubes may be permitted to hang freely from the supporting element 12. The absence of a core and the construction of the tubes in predetermined, carefully calculated sizes obviates any tendency to whip under electrical stresses; at the same time, the great multiplicity of points 6 provide electrical coronas of greater efficiency than has heretofore been possible, while the general construction reduces the consumption of power to a low point and reduces the supporting means to its simplest form.

Various modifications may be made within

the scope of the claims without departing from the nature of my invention, as set forth in the appended claims.

I claim:

- 5 1. A discharge electrode for electrical precipitators comprising a tube closed at its opposite ends and provided upon its outer surface with a multiplicity of relatively fine serrations, each of which is continuous in the 10 direction of the tube, and the discharge apex of each of which is in such close parallel relation to the discharge apices of its neighbors as, in effect, to come within the range 15 of influence thereof, whereby concentrated discharges tending to form disruptive arcs are prevented, said tube having an empty axial bore, and means whereby said electrode is freely suspended.
2. A discharge electrode for electrical precipitators comprising a tube closed at its opposite ends and provided upon its outer surface with a multiplicity of relatively fine serrations, each of which is continuous in the 20 direction of the tube, and the discharge apex of each of which is in such close parallel relation to the discharge apices of its neighbors, as, in effect, to come within the range 25 of influence thereof whereby concentrated discharges tending to form disruptive arcs are prevented, said tube having an empty axial bore, a lead covered sleeve adapted for connection with a supporting element, and means whereby said electrode is freely suspended in said sleeve.
3. A discharge electrode for an electrical precipitator comprising a tube closed at its opposite ends and provided upon its outer surface with a multiplicity of relatively fine serrations, said tube having an empty axial 25

bore, a lead-covered sleeve adapted for connection with a supporting element, a filling of lead whereby said electrode is freely suspended in said sleeve, and a pin extending transversely through said sleeve and tube to fix the latter against relative lengthwise movement.

4. A discharge electrode for an electrical precipitator comprising a tube closed at its opposite ends and provided upon its outer surface with a multiplicity of relatively fine serrations, said tube having an empty axial bore, a lead-covered sleeve adapted for connection with a supporting element, a filling of lead whereby said electrode is freely suspended in said sleeve, a pin extending transversely through said sleeve and tube to fix the latter against relative lengthwise movement, and a cap of lead covering the end of said sleeve and the opposite ends of said pin.

5. In a precipitator of the kind described, the combination of a plurality of tubular collecting electrodes, a supporting channel having a lead covering, a plurality of lead-covered sleeves connected with said channel, discharge electrodes comprising tubes of lead provided with a multiplicity of relatively fine serrations, fillings of lead whereby said electrodes are freely suspended in said sleeves to hang freely from said channel into said collecting electrodes, pins extending transversely through said sleeves and tubes for fixing the latter against relative lengthwise movement, and caps of lead surrounding the tubes and covering one end of said sleeves and the opposite ends of said pin.

In testimony whereof I have hereunto set my hand.

GEORGE R. LEWERS.
